UNITED STATES PATENT OFFICE.

WILLIAM MUMBRAUER, OF NEW YORK, N. Y.

CLOSURE FOR PEEPHOLES AND THE LIKE.

Application filed May 12, 1927. Serial No. 190,703.

This invention relates to peep holes and the like and to improved closures therefor and means for operating them. My invention has many applications among which may be mentioned doors in apartment houses, lodges; also, enclosures where certain precautions are taken for guarding lives and property, etc.

A principal object of my invention is to provide means for raising and lowering the gate for the peep hole.

Another principal object is to provide mechanism adapted to readily raise or lower the gate from the inner side of the inclosure, and to anchor the gate against movement by any attempt to raise or lower the same from a position exterior of the inclosure.

Another object of my invention is to provide means for safe-guarding persons or property within the inclosure from exterior attacks through the peep holes by providing means for closing the gate and automatically locking the same in closed position against any attempt from the exterior to open the same.

It is a further object to provide a device of this character in which the shutter may be maintained in any adjusted position.

Other objects will be apparent from reading this specification in connection with the accompanying drawings in which,

Figure 1 is an elevation view of my device looking at the inner side thereof, in which the gate is in closed position;

Figure 2 is a vertical cross section taken along the line 2—2 of Figure 1;

Figure 3 is an elevation of my device looking at the inner side thereof in which the gate is shown in raised position, the peep holes being uncovered for service; and

Figure 4 is a horizontal cross section taken along the line 4—4 of Figure 3.

Referring now in detail to the drawings in which similar reference characters refer to similar parts throughout: 5 represents one of the sides of an inclosure in which is mounted the peep hole plate 6 provided with the peep holes 20, 20. The plate is provided with vertical guides 7, one at each side thereof, between which is adapted to slide the gate 8 in an upward and downward direction in the embodiment shown in the drawings, purposes of these guides being to restrict lateral movement of the gate and to maintain it in adjusted position and to add strength to the peep hole plate 6.

Adjacent to the inner surface of the gate 8 is a carrier 9 provided with the projecting arms 10—11 in slidable relation with the saddles 12 and 13 respectively, which saddles are secured to the peep hole plate 6 by the screws or other fastenings 14, and which also secure the carrier to the plate 6. Mounted on the gate 8 are detents or dogs 15 which are swivelly connected thereto by the pins 16. Integrally mounted in the dogs 15 are pins 18 which project into the slots 17 of the carrier and operate in slidable relation therewith.

Gate 8 also has a vertically extending portion 25 and a depending portion 26, the latter serving the purpose of affording means for holding the dogs 15 out of engagement with the guides 7, as by the operator holding down the said portion 26 while pressing upwardly on handle 19 of the carrier 9. In other words, by means of depending portion 26 and handle 19 complete control of the dogs 15 may be had.

In operation, the gate 8 is raised and lowered by manipulation of the handle 19 which acts upon the carrier 9 and through the pins 16 on the gate 8. Upon this carrier being raised, the pins 18 will draw the dogs inwardly through cooperation with their respective slots 17, sufficiently to insure a clearance between the ends of said dogs and the guides 7. If, on the other hand, it is attempted to raise the said gate by direct manipulation of the gate itself, upon any vertical shift thereof, the pins 17 will in cooperation with their respective slots, swing the dogs outwardly against the guides 7, and further movement of the gate will anchor the ends of the dogs into said guides, and thus hold the gate against further movement. In the manipulation of the carrier in a downward direction, the pins 18 will ride in the slots at their outer ends and maintain the dogs 15 out of engaging contact with the guides 7. Furthermore, by means of the dogs 15 the gate 8 may be maintained in any raised position.

I have described what I believe to be the best embodiment of my invention. I do not wish to be limited in patent protection to the embodiment shown, however, but what I desire to cover by Letters Patent is set forth in the appended claims.

I claim:

1. In combination with a peep hole structure, a slidable gate adapted to cover and

- clear the peep hole opening, guides for said gate, detents swivelly mounted on said gate, a carrier, pins mounted in said detents, said pins being adapted to operate in slots in said carrier and withdraw the ends of said detents from contact with said guides upon direct operation of said carrier and to bind in said guides upon indirect operation of said carrier.
- 10 2. In combination with a peep hole structure, a slidable gate adapted to cover and clear the peep hole opening, guides adapted to maintain the gate in alignment, a carrier loosely connected to and adapted to operate said gate, and means for maintaining said carrier in operative connection with said gate.
- 15 3. In combination with a peep hole structure, a slidable gate adapted to cover and

clear the peep hole opening, a carrier loosely connected with said gate and adapted to operate the same, means for maintaining said carrier in connection with said gate, and means for anchoring said gate, except when operated by said carrier.

25 4. In combination with a peep hole structure, a slidable gate adapted to cover and clear the peep hole opening, a carrier adapted to operate said gate, said carrier being loosely connected to said gate and secured in slidable relation to said peep hole structure, detents carried by said gate adapted to anchor the gate against operation, except through said carrier.

30 In testimony whereof I have affixed my 35 signature to this specification.

WILLIAM MUMBRAUER.
